UNITED STATES PATENT OFFICE.

FREDERICK ARTHUR COOPER, OF LEICESTER, ENGLAND, ASSIGNOR TO UNITED SHOE MACHINERY COMPANY, OF PATERSON, NEW JERSEY, A CORPORATION OF NEW JERSEY.

COMPRESSING-MACHINE.

1,015,784.

Specification of Letters Patent. Patented Jan. 30, 1912.

Application filed September 19, 1910. Serial No. 582,702.

To all whom it may concern:

Be it known that I, FREDERICK A. COOPER, a subject of the King of England, residing at Leicester, Leicestershire, England, have 5 invented certain Improvements in Compressing-Machines, of which the following description, in connection with the accompanying drawings, is a specification, like reference characters on the drawings indicating like parts in the several figures.

This invention relates to compressing machines and more particularly to machines for compressing and molding heels or top lifts for boots or shoes. The present invention may with advantage be embodied in a 15 machine of the type disclosed in U. S. Letters Patent No. 776,823, granted December 6, 1904. In compressing machines of this type some difficulty has heretofore been experienced at times owing to the accidental jamming of a heel or top lift blank in the mold or the introduction of a piece of material not of the proper size or form, sometimes resulting in failure of the ejecting 20 mechanism and breakage of some of the parts of the machine.

One object of the present invention, accordingly, consists in the provision of an 30 ejecting mechanism for compressing machines, which shall be effective to eject a compressed blank in the usual operation of the machine, but which has provision for yielding when a blank becomes jammed in the mold, or other resistance causes excessive 35 strain.

In a preferred form of construction, constituting one embodiment of the invention, which for purposes of illustration is herein-after specifically described and shown in 40 the accompanying drawings, the yielding feature previously referred to may be introduced in a train of connections between a top lift plate vertically movable within the compressing mold and the means by which 45 the actuation of such plate is effected.

The arrangement may conveniently comprise a slightly bent toggle connecting a plurality of members in the train of connections above referred to and a spring normally 50 maintaining said toggle extended but permitting the toggle to be broken when excessive resistance is encountered by the plunger or spindle upon which the top lift plate is mounted.

55 In the accompanying drawings,—Figure

1 is a view in side elevation, partly in section, showing a portion of a heel compressing machine with the invention applied thereto; Fig. 2 is a front elevation, partly in section, of the ejecting mechanism shown 60 in Fig. 1; and Fig. 3 is a view, similar to Fig. 1, showing the heel ejecting mechanism in the position which it assumes when a heel becomes jammed in the mold.

In the machine of the prior patent, to 65 which machine this invention is described as being applied, there is a heel ejecting plunger located in a vertical position below, and supporting, a top lift plate. The top lift plate constitutes the bottom of a mold 70 in which a heel blank may be compressed and the said plunger is arranged to be engaged at certain times during the operation of the machine by an arm secured to a rock-shaft journaled in the reciprocating cross-head of the machine, all of which will clearly appear upon reference to the said patent.

According to the present invention, the heel ejecting plunger 2 depends from the top lift plate 4 which constitutes the bottom 80 of a die or mold 6 within which the blank 8 is compressed.

10 represents the vertically movable cross-head which is reciprocated during the operation of the machine. The plunger 2 is 85 operated by an arm 12 which extends beneath said plunger and is secured to the rock-shaft 14. According to the present invention, the arm 12 is arranged to yield when the movement of the plunger 2 is resisted. For this purpose another lever arm 16 is loosely mounted upon the rock-shaft 14 and is provided at its upper end with a hook shaped extension 18. Another arm 20 extends downwardly from the arm 16 and 90 is provided at its lower end with a cam roll 22 which travels in a path 24 in a cam plate 26 which is secured upon a stationary part of the machine frame.

Adjacent to the arm 16 and secured to the 100 rock-shaft 14 is an arm 28 having its free or lower end in proximity to the hook shaped portion 18 of the lever 16. The arms 12 and 28, both being secured to the rock-shaft 14, constitute a lever. The ends of the arms 105 28 and 16 are coupled together by a toggle 30, 32, the central joint 34 of which is connected by a plate 36 and spring 38 with the upper extremity of the arm 28 as shown at 40. The spring 38 connecting the toggle 110

joint with a continuation of the lever 28 normally tends to maintain the toggle in its unbroken or straightened condition as shown in Fig. 1, in which case the said toggle forms a connecting link between the hook shaped end 18 of the arm 16 and the arm 28. The toggle is arranged in such a manner that when in its extended condition it is not in a straight line but is held in a position approximating thereto by the spring 38 so that the toggle will not be prevented from breaking when excessive resistance is encountered by the machine. For this purpose the links 30 and 32, forming the elements of the toggle, are provided with co-operating stop pieces 42, 44, which normally maintain the toggle in a position approximating to a straight line as above set forth and as clearly shown in Fig. 1.

Each element of the toggle is connected to its respective arm or lever, preferably by an eccentric joint, as indicated at 46, so that the toggle may be adjusted in order to compensate for wear of the various parts or to provide means for adjusting the limits of the stroke of the ejector arm 12.

For operating the ejector mechanism the cam plate 26 performs its functions in a manner similar to the corresponding element in the machine disclosed in the patent above referred to, the cam plate having a movable latch or switch 48 located in the cam recess 24. The switch 48 is pivoted to the plate 26 and has an arm 50 to which is attached a weight 52. The weight 52 normally holds the switch in a position extending across the cam recess, as shown in dotted lines in Fig. 1, but permits the switch to be moved during the reciprocations of the cross-head 10. The switch 48 divides the cam recess into two parts. When the reciprocating cross-head is rising the roll 22 carried on the lever 20 moves in the path to the right of the switch 48 and when the head is descending the roll moves in the path to the left of the said switch, all of which will be clearly apparent from an inspection of Figs. 1 and 3.

In the operation of the ejector actuating means the downward movement of the reciprocating cross-head 10 causes the cam roll 22 on the arm 20 to be moved in the cam groove 24 and, through the arm 16, the toggle 30, 32 and the arm 28, to oscillate the rock-shaft 14 and in consequence to move the ejector actuating lever 12 upwardly into such a position as to elevate the plunger 2 and plate 4 to eject the heel blank from the machine. Should, however, the blank become jammed and prevent the ejecting plunger 2 from being operated the excessive pressure will, on the continued descent of the head, be transmitted to the toggle joint through the arms aforesaid, which toggle, owing to its slightly bent position, will now

be completely broken against the tension of the spring 38, as clearly shown in Fig. 3. During the reverse movement of the reciprocating head the spring 38 will restore the toggle to its normal or unbroken condition shown in Fig. 1.

The construction and arrangement of the parts described insures that damage to the machine and injury to the work, due to a blank becoming jammed or other obstructing causes, will be completely avoided.

While a preferred and effective construction of the invention as applied to a heel compressing machine of the class disclosed in the U. S. patent hereinbefore referred to has been described in detail, it should be understood that the invention is not limited to the particular construction and arrangement of parts described, as these are capable of variation without departure from the spirit and scope of the invention which will be defined in the appended claims.

Having thus described the invention, what is claimed as new and desired to be secured by Letters Patent of the United States is:—

1. In a compressing machine, the combination of an ejecting member for engaging a blank to be removed, a positively operated device for actuating said ejecting member and normally rigid connecting means between said actuating device and said ejecting member, said connecting means being arranged to yield when subjected to a predetermined excessive pressure and to readjust itself automatically when released from said pressure.

2. In a compressing machine, the combination of an ejecting member for engaging a blank to be removed, a positively operated device for actuating said ejecting member, and means comprising a normally extended toggle connecting said ejecting member and said actuating device, said toggle being breakable under a predetermined pressure.

3. In a compressing machine, the combination of an ejecting plunger, a cam operated lever for actuating said plunger and means connecting said lever and plunger comprising a normally extended toggle, said toggle being breakable under excessive pressure.

4. In a compressing machine, the combination of an ejecting member for engaging a blank to be ejected, a positively operated lever for actuating said ejecting member and connections between said lever and said member, said connections comprising a slightly bent toggle and a spring normally maintaining said toggle in its extended position but permitting said toggle to be broken when excessive resistance is encountered by the ejecting member.

5. In a compressing machine, the combination of an ejecting member for engaging

a blank, a positively operated actuating device for actuating said ejecting member and a toggle connecting said ejecting member and actuating device, each element of the
5 toggle being provided with a stop, which stops normally maintain the toggle nearly, but not quite, in a straight line.

In testimony whereof I have signed my name to this specification in the presence of two subscribing witnesses.

FREDERICK ARTHUR COOPER.
